United States Patent Office.

JOHN LAMB, OF JEFFERSONVILLE, NEW YORK.

Letters Patent No. 79,662, dated July 7, 1868.

IMPROVED WASHING-MACHINE.

The Schedule referred to in these Letters Patent and making part of the same.

TO ALL WHOM IT MAY CONCERN:

Be it known that I, JOHN LAMB, of Jeffersonville, in the county of Sullivan, and State of New York, have invented certain new and useful Improvements in Washing-Machines; and I do hereby declare that the following is a full, clear, and exact description thereof, reference being had to the accompanying drawings, and to the letters of reference marked thereon, which form a part of this specification, in which—

Figure 1 is a plan view, and

Figure 2 a transverse vertical section.

The nature of this invention consists in the employment of a cylinder, provided with strips of India rubber set in said cylinder edgewise, in combination with a vibrating beating-rod, arranged substantially as hereinafter set forth.

To enable others skilled in the art to make and use my invention, I will now describe its construction and operation.

A represents a common wash-tub, near the centre of which is pivoted or hung the cylinder B. One of the journals of the cylinder may be the crank, d, which is adjustable, thus enabling the cylinder to be removed when desirable. e e represent strips of India rubber, secured longitudinally and edgewise in cylinder B. g represents a stationary rod, around each end of which are the spiral springs h h, partially shown in fig. 2. One end of these springs is turned up and firmly secured to the vibrating-rod i. This rod may be either fluted or smooth.

The operation is simply to supply the tub with water, and draw the clothing between the cylinder B and the vibrating-rod i, which will, by their action, thoroughly cleanse them; without tearing or injuring them in any way.

What I claim as new, and desire to secure by Letters Patent, is—

The cylinder B, when provided with strips of India rubber, in the manner set forth, in combination with the fluted vibratory rod i, arranged and operated as and for the purpose set forth.

In testimony that I claim the foregoing as my own, I affix my signature, in presence of two witnesses.

JOHN LAMB.

Witnesses:

LEANDER M. YOUNG,

JOSIAH SMITH.
